(57) **CLAIM**

The ornamental design for a headset, as shown and described.

DESCRIPTION

FIG. 1 is a perspective front view of a headset showing our new design;

FIG. 2 is a perspective front view of the headset from FIG. 1 showing our new design with the earpieces in an alternate position;

FIG. 3 is a front view of the headset from FIG. 1;

FIG. 4 is an enlarged perspective view of the right earpiece from FIG. 1, shown in isolation and in a larger scale;

FIG. 5 is a perspective front view of a headset showing an alternate embodiment of our new design;

FIG. 6 is a right side view thereof;

FIG. 7 is a left side view thereof;

FIG. 8 is a rear view thereof; and,

FIG. 9 is a front view thereof.

The broken line showing of the environmental structure of the headset and the unshaded region within the broken lines in FIGS. 1-9 is for illustrative purposes only and forms no part of the claimed design.
